(57) **CLAIM**

The ornamental design for a finger ring, as shown and described.

DESCRIPTION

FIG. 1 is a perspective view of a finger ring showing my new design;

FIG. 2 is a front perspective view thereof;

FIG. 3 is a rear perspective view thereof;

FIG. 4 is a front view thereof;

FIG. 5 is a rear view thereof;

FIG. 6 is a side elevational view thereof;

FIG. 7 is an elevational view of the opposite side thereof;

FIG. 8 is a top plan view thereof;

FIG. 9 is a bottom plan view thereof; and,

FIG. 10 is a view showing the finger ring slightly expanded as it fits on a wearer's finger.

The broken-line portions in FIGS. 1, 2 and 10 are for illustrative purposes only and form no part of the instant design.
